UNITED STATES PATENT OFFICE.

IRA H. SPENCER, OF WEST HARTFORD, CONNECTICUT, ASSIGNOR TO THE ORGAN POWER COMPANY, OF HARTFORD, CONNECTICUT, A CORPORATION OF CONNECTICUT.

ORGAN-BLOWER.

1,158,738.

Specification of Letters Patent.

Patented Nov. 2, 1915.

Application filed September 13, 1912. Serial No. 720,123.

To all whom it may concern:

Be it known that I, IRA H. SPENCER, a citizen of the United States, and a resident of West Hartford, in the county of Hartford and State of Connecticut, have invented 5 a new and Improved Organ-Blower, of which the following is a specification.

My invention relates to the class of apparatus used for supplying pressure to musical instruments and especially to pipe organs, although it will be understood that the invention is not necessarily limited to such use, and an object of the invention, among others, is to provide an apparatus of this 10 class that shall be simple and inexpensive in construction and extremely efficient in operation.

One form of structure embodying my invention and in the construction and use of 15 which the objects herein set out, as well as others, may be attained is illustrated in the accompanying drawing, in which—

Figure 1 is a view in vertical central section through an apparatus embodying my invention. Fig. 2 is a view in vertical cross section through the same on plane denoted by dotted line 2—2 of Fig. 1.

In the accompanying drawing the numeral 5 denotes a casing, composed of any 20 suitable material, preferably round in cross section, and with a recessed chamber 6 at one end in which a motor 7, herein shown as of the electric type, is located. The casing also contains a blower chamber 8 formed 25 by the outer wall of the casing and the end walls 9, 10, the former dividing the motor or recessed chamber 6 from the blower chamber, and the wall 10 forming the opposite and outer end wall of the blower chamber. These end walls 9, 10 are composed 30 of circular plates, in the form of casing herein shown, each plate having a flange 11 resting snugly against the inner surface of the casing.

The blower chamber is divided into a 35 number of pressure compartments 12, of any suitable number, three being shown herein, these pressure compartments being formed by diaphragms 13, each having a flange 14 resting snugly against the inner 40 surface of the casing and each provided with a circular opening 15 for the passage of air from one pressure compartment to another.

Each pressure compartment is divided

into a fan chamber 16 and a deflector chamber 17, this being effected by means of separating plates 18 supported on studs 19 secured to the end walls and diaphragms. These studs are preferably provided with shoulders 20 at each end abutting against the end wall and plate and with nuts 21 fitting the threaded ends of the studs to hold the parts in position. Any suitable number of studs may be employed to support the 60 separating plates, and they are located preferably near the periphery of the separating plates. These plates are of a size to leave passages 22 between the periphery of the plates and the inner surface of the wall of 65 the casing for the passage of air from one fan chamber into the next succeeding deflector chamber, in the latter of which deflectors 23 are located to influence the flow of air currents toward the center of the 70 casing for passage through the central openings 15 to the next succeeding pressure compartment.

A shaft 24 projects from the motor 7 through the several end walls, diaphragms 80 and separating plates, and a fan, consisting of a number of blades 25, supported by a fan base 26 is secured to the shaft, one fan in each of the chambers 16. The end walls and diaphragms may be secured to the casing in any suitable and convenient manner, as herein shown, the end wall 9 resting against angle pieces 27, and spacing pins 28 secured in this end wall and diaphragm holding the several parts properly spaced. 85

In the form of apparatus illustrated herein the end wall 10 forms one wall of the first pressure compartment from the inlet toward the casing. This wall, as well as the other walls at the inlet to each of the 90 pressure compartments, has a flat face 33 located substantially at right angles to the axis of the casing and extending for a substantial distance from the periphery of the wall, as shown herein, nearly half way to 100 the center. From this point the plate is dish shaped to provide a recess constituting a fan chamber, within which a fan is located. The discharge channels 29 are thus located between the plates 18 and the walls 105 and diaphragms, which channels extend from the periphery of said depressions or fan chambers to the periphery of the plates.

The studs secured to the end wall 9, in the structure shown herein, are shouldered 110

- at both ends to receive the end wall and separating plate, nuts being applied to both ends of the studs to hold the parts in position. As to the studs secured to the dia-
 phragms the inner ends are preferably
 screw threaded into the diaphragms, the
 opposite ends being shouldered to receive a
 separating plate 18 and threaded to receive
 the nuts to hold said plate in place.
- 10 The arrangement of the plates 18 provides
 discharge channels 29 extending from the
 periphery of the fans to the edge of the plate
 and around said edge, and this manner of
 mounting the plates to form discharge chan-
 nels enables the size and form of the latter
 to be varied to suit any conditions that may
 arise. The fan bases are recessed as at 30
 to provide space for packing means at the
 center of the plates 18. The holes for the
 20 shaft 24 through the plates are somewhat
 larger than the shaft and a packing 31
 closely fitting the shaft is placed against
 each plate and a collar 32 is employed to
 hold the packing in place.
- 25 The structure herein shown and described
 may be departed from to a greater or lesser
 extent and yet embody the invention as de-
 fined by the appended claims and I do not
 therefore limit the invention to a structure
 30 exactly like that herein disclosed.

I claim—

1. In combination with a casing having
 inlet and outlet openings, walls extending
 across the casing and forming the bound-
 35aries of a pressure compartment, one of said
 walls also forming the boundary of a fan
 chamber and having an opening at the center
 thereof, a set of studs secured to one of
 said walls and projecting from the face on
 40 opposite sides of the center thereof, a sepa-
 rating plate mounted on the ends of said
 studs and forming one wall of said fan
 chamber, a fan located within said chamber
 and with its end terminating at a substantial
 45 distance from the periphery of the sepa-
 rating plate to provide a discharge channel
 between said separating plate and the wall of
 the compression chamber, and means for
 rotating the fan.
- 50 2. In combination with a casing having
 inlet and outlet openings, walls extending
 across the casing and forming the bound-
 55aries of a compression chamber, one of said
 chamber and having a central opening in
 said recess, a set of studs projecting from
 the face of one of said walls on opposite
 sides of the center thereof, a plate secured
 60 to the ends of said studs and spaced from
 said wall, said plate being smaller in diam-
 eter than the interior of the casing and
 forming the opposite and stationary wall
 of said fan chamber, a fan located within
 65 said recess and of a diameter substantially
 less than the diameter of said plate to pro-

vide a discharge channel of substantial
 length between said wall and plate and be-
 yond the periphery of the fan, and means for
 rotating the fan.

3. In combination with a casing having 70
 inlet and outlet openings, walls extending
 thereacross to form the boundaries of a com-
 pression chamber, one of said walls being re-
 cessed at its center to form a fan chamber
 and the balance of said wall being flat and 75
 located at right angles to the axis of the cas-
 ing, said wall having an opening at the center
 thereof, a set of studs extending from the
 opposite wall, a plate less in diameter than
 the interior of the casing supported on the
 80 ends of said studs and spaced from the re-
 cessed wall and extending parallel with the
 flat portion thereof, the periphery of said
 plate being located at a substantial distance
 from the edge of the fan chamber to pro-
 vide a discharge channel, a fan located in
 85 said chamber, and means for rotating the
 fan.

4. In combination with a casing having 90
 inlet and outlet openings, walls extending
 across said casing and forming the bound-
 95aries of a compression chamber, one of said
 walls having an opening at the center there-
 of, a set of spacing pins secured in screw
 threaded openings in the opposite wall to 95
 adjustably space said walls apart, studs re-
 movably secured to said opposite wall, a
 plate removably secured to said studs and
 spaced from the wall having the central
 opening, a fan located between said plates
 100 substantially less in diameter than said plate
 to provide a discharge channel between said
 plates, and means for rotating the fan.

5. In combination with a casing having
 inlet and outlet openings, a wall extending
 across said casing and having a concaved de-
 pression at the center with a flat peripheral
 portion located at right angles to the axis
 of the casing, a fan having its base located
 in the bottom of said depression and pro-
 jecting outwardly therefrom, a flat plate dis-
 posed parallel with the flat peripheral portion
 of said wall, forming one wall of the
 fan chamber and one wall of a discharge
 space, said plate being of a diameter ma-
 terially greater than that of the fan, and
 means for supporting and rotating the fan.

6. In combination with a casing having a
 passage through one wall thereof, walls ex-
 tending across said casing and each having
 a concaved depression at the center with
 a flat peripheral portion located at right
 angles to the axis of the casing, said
 walls being disposed in parallel relation and
 one having an inlet opening at its center, a
 flat plate located between said walls and
 spaced from one to provide a fan chamber,
 said plate having its peripheral portion lo-
 cated opposite the flat portion of said one
 wall to provide a discharge space with paral- 125
 130

lel walls, a fan located in said fan chamber, and means for supporting and rotating the fan.

7. In combination with a casing having 5 a passage through one wall thereof, a wall extending across said casing to close it, a set of studs secured to said wall on opposite sides of the center thereof, a flat plate secured upon the ends of said studs, a set of 10 pins secured to said walls upon opposite sides of the center thereof, a wall extending across said casing and resting against said pins to constitute a fan chamber between said wall and plate, a fan located within 15 said chamber, and means for supporting and rotating the fan.

8. In combination with a casing of round tubular form having a passage through one wall thereof, walls extending across said 20 tube at a distance from each end thereof,

said walls having a depressed central portion and a flat peripheral portion arranged in parallel relation, one of said walls having an inlet opening at its center, a flat plate disposed between said walls and having its 25 periphery arranged in parallel relation to the flat portion of one of said walls to provide a discharge space having parallel walls, said plate being of a diameter less than the diameter of said casing to provide for the 30 passage of air about the periphery of said plate, a fan located in a fan chamber constituted by the depressed central portion of one of said walls, and means for supporting and rotating the fan.

IRA H. SPENCER.
